UNITED STATES PATENT OFFICE.

THEODORE A. KOCHS, OF CHICAGO, ILLINOIS, ASSIGNOR TO THEO. A. KOCHS COMPANY, OF CHICAGO, ILLINOIS, A CORPORATION OF ILLINOIS.

DESIGN FOR A BODY PORTION FOR CHAIRS.

SPECIFICATION forming part of Design No. 37,228, dated November 15, 1904.

Application filed March 21, 1904. Serial No. 199,294. Term of patent 7 years.

To all whom it may concern:

Be it known that I, THEODORE A. KOCHS, a citizen of the United States, residing at Chicago, in the county of Cook and State of Illinois, have invented a new, original, and ornamental Design for the Body Portion of a Chair, which design is illustrated in the accompanying drawing.

The illustration is a perspective view.

What I claim as new, and desire to secure to by Letters Patent, is—

The ornamental design for the body portion of a chair, as shown.
